CLAIM

The ornamental design for a travel bottle as shown and described.

DESCRIPTION

FIG. 1 is a perspective view of a travel bottle showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is an enlarged top plan view thereof;

FIG. 8 is an enlarged bottom plan view thereof;

FIG. 9 is a partial enlarged view of portion 9 in FIG. 1; and, FIG. 10 is a partial enlarged view of portion 10 in FIG. 1. The broken lines depict portions of the travel bottle and form no part of the claimed design.

The dot dash line is included for the purpose of illustrating the bounds of the enlarged view and forms no part of the claimed design.

1 Claim, 10 Drawing Sheets(56)
